UNITED STATES PATENT OFFICE

HOMER J. MESSIER AND JAMES K. DONAGHY, OF NEW BEDFORD, MASSACHUSETTS

DESIGN FOR A BUILDING

Application filed September 21, 1932. Serial No. 45,013. Term of patent 14 years.

To all whom it may concern:

Be it known that we, HOMER J. MESSIER and JAMES K. DONAGHY, citizens of the United States, residing at New Bedford, in the county of Bristol and State of Massachusetts, have invented a new, original, and ornamental Design for a Building, of which the following is a specification, reference being had to the accompanying drawing, forming part thereof.

Figure 1 is a front perspective view of a building, showing our new design.

Figure 2 is a top plan view thereof.

We claim:—

The ornamental design for a building as shown.

HOMER J. MESSIER.
JAMES K. DONAGHY.
